CLOSURE MEANS FOR HANDBAGS

Joseph Feigen, Brooklyn, N. Y.

Application March 22, 1946, Serial No. 656,397

2 Claims. (Cl. 150—42)

1

This invention relates to new and useful improvements in handbag construction.

Heretofore, handbags with slide fastener closures for the tops thereof have had mouths which could not be fully opened at their ends. When the slide fastener closure was extended along a side of the bag to remedy this disadvantage, another detriment resulted due to the fact that the bag was then opened along one side as well as at the top, causing contents to be spilled therefrom.

An object of the invention, therefore, is to provide a handbag with expandible closed sides and a slide fastener closure which permits the sides to be fully expanded in open position.

This and other objects are accomplished by providing a frame and closure means for a handbag having two opposingly disposed expandible sides or inwardly folding gussets and a main compartment with a mouth at the top thereof. The frame is comprised of two L-shaped frame members positioned with their long legs extending along and secured to the mouth of the bag and their short legs extending outside of and removed from the same expandible bag side, the lower ends of the short legs being rotatably joined to each other by hinge means. The closure means consists of slide fastener elements and a slide, the slide fastener elements extending along and to the outside of the frame members, the mouth portion of said elements being secured to the bag and the side portion of the slide fastener elements being secured to the short legs of the frame members away from the adjacent expandible side. The closure is effected with the slide in the slide fastener terminus at the mouth end. When the bag is in open position with the slide in the side of the slide fastener terminus, the adjacent expandible side can be fully opened, the short legs of the frame being rotatably attached at their lower end and the slide fastener elements being separable.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a slide fastener handbag constructed in accordance with the invention herein, the bag being shown in open position with portions of its front wall broken away to reveal construction details.

Fig. 2 is a top view of the handbag.

Fig. 3 is an end view of the handbag.

2

Fig. 4 is a sectional view through the line 4—4 of Fig. 2.

Fig. 5 is a perspective view of the hinged frame member of the handbag.

5 In the drawings and in the specification, in which like reference numbers designate similar elements, a lady's handbag 10, having a body portion 11 and two oppositely disposed expandible side gussets 12, is provided with frame and closure 10 means embodying the invention herein and comprising two L-shaped frame members 13 rotatably joined to each other by hinge means 14 and a slide fastener closure 15.

The body portion 11 is formed to provide front 15 and back walls 16. Each gusset 12 is foldable inwardly and extends between the walls at their ends from the bottom to a line below the top edges 17 of the walls 16.

Each of the frame members 13 is positioned 20 with a long leg 18 extending along and secured to the inside face of a wall 16 below its top edge 17 and between and above the gussets, and with a short leg 19 detached from the bag and extending over one of the gussets and resting beyond it near its outside face (see Figs. 1 and 2). The two frame members 13 are rotatably joined to each other at the free ends of their short legs 19 by the hinge means 14.

The slide fastener closure 15 is provided with 30 interlocking elements 20 and a tab slide 21 made in the usual way. The interlocking elements 20 extend from a terminus 22 above the end of each long frame leg 18 to a terminus 23 adjacent and outside of the end of each short frame leg 19, 35 the closure being effected when the tab slide 21 is at the terminus 22, and the mouth of the bag being fully open when the slide is at the terminus 23.

The course of the slide fastener between the 40 termini 22 and 23 is parallel along and to the outside of the frame member 13, thus following an L-shaped path, with the fastener on leg 24 effecting the closure of the mouth of the bag, and the short slide fastener on leg 25 permitting the bag mouth to be fully opened along the side 45 25 of the slide fastener terminus 23. This is the essence of the invention since it permits the slide fastener on side 25 to be fully opened without being physically disconnected, thus preventing the bag contents from being spilled out.

To accomplish this result, the short legs of the frame members and the short courses of the slide fastener extend over and beyond the adjacent side gusset and are detached therefrom.

55 While the frame members have been described as having long and short legs, it is understood

that the same result can be effected by using a vertical frame member detached from and extending beyond the side gusset and attaching the top of the frame member to the walls of the bag.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A handbag having front and back walls interconnected at their respective bases and having free upper edges, said front wall having side edges oppositely disposed and adjacent the side edges of said back wall, a gusset secured to each pair of oppositely disposed adjacent side edges, each of said gussets being inwardly foldable and positioned intermediate said front and back walls, a pair of L-shaped frame members each having an elongate leg and a short foot, one of said frame members having its leg secured to said front wall adjacent to and substantially parallel to said upper edge, the other of said frame members having its leg secured to said back wall adjacent to said upper edge and extending substantially parallel thereto and to said first mentioned leg, each foot of said frame members extending downwardly from their respective legs and positioned within a fold formed in one of said gussets common to the foot of each of said frame members, the foot of each of said frame members being completely detached from said walls and said gussets, each of said frame members being pivotally connected adjacent the free end of each foot, a series of slide fastener elements mounted on the foot of said first frame member and having an extension thereof secured to said front wall adjacent and substantially parallel to the leg of said first frame member, a series of slide fastener elements mounted on the foot of the other of said frame members and having an extension secured to said back wall adjacent and substantially parallel to the leg of said other frame member, and a slide fastener mounted on said first and second

series of said fastener elements operable to engage and disengage each of said series of fastener elements, one with the other.

2. In a handbag having front and back walls interconnected at their bases and having free upper edges and gussets secured between the oppositely disposed side edges of the walls to be folded inwardly between the adjacent faces of the walls, a pair of frame members each having an elongated top leg and a short foot depending from one end thereof, said legs being secured to the inner faces of the top edges of the walls, said feet being extended parallel to each other and depending into the fold formed in one of the gussets, hinge means secured to the bottom ends of said feet pivotally connecting said frame members together, continuous rows of slide fastener elements mounted on the adjacent edges of the legs and feet of said frame members, and a slide fastener pull tab engaging said slide fastener elements for connecting said slide fastener elements to retain said frame members closed when said pull tab is moved to one end of said frame members and for disengaging said slide fastener elements to free said frame members to be pivoted relative to each other when said pull tab is moved to the other end of said frame members.

JOSEPH FEIGEN.
